(57) CLAIM

The ornamental design for a cosmetic package as shown and described.

DESCRIPTION

FIG. 1 is a perspective view of a cosmetic package showing our new design;

FIG. 2 is a front view of the cosmetic package of FIG. 1; FIG. 3 is a back view of the cosmetic package of FIG. 1; FIG. 4 is a bottom isometric view of the cosmetic package of FIG. 3;

FIG. 5 is a left side view of the cosmetic package of FIG. 1; FIG. 6 is a right-side view of the cosmetic package of FIG. 1;

FIG. 7 is a top view of the cosmetic package of FIG. 1; FIG. 8 is a bottom view of the cosmetic package of FIG. 1; and,

FIG. 9 is a top perspective view of the cosmetic package of FIG. 1, shown with a cap thereof in an open position. The broken lines in the drawings depict portions of the cosmetic package that form no part of the claimed design.

1 Claim, 9 Drawing Sheets
